United States Patent

Des. 235,759
Patented July 8, 1975

235,759

SKI CARRIER

Ronald W. Parsons, Tottenham, Ontario, Canada, assignor
to A.L. & W. Limited

Filed Jan. 8, 1974, Ser. No. 431,613

Claims priority, application Canada July 30, 1973

Term of patent 14 years

Int. Cl. D12—16

U.S. Cl. D12—157

FIG. 6.

FIG. 1.

FIG. 5.

FIG. 1 is a perspective view of a ski carrier, showing my new design;

FIG. 2 is a side elevational view thereof, it being understood that the opposite side is a mirror image of the side shown herein;

FIG. 3 is a top plan view thereof;

FIG. 4 is a bottom plan view thereof;

FIG. 5 is a sectional view thereof taken along the lines V—V of FIG. 2; and

FIG. 6 is an enlarged fragmentary perspective view of the central portion thereof.

I claim:

The ornamental design for a ski carrier, as shown and described.
